DESIGN FOR A MEMORIAL TABLET

Alan Figatner, Brooklyn, N. Y.

Application April 9, 1946, Serial No. 128,421

Term of patent 7 years

(Cl. D29—23)

To all whom it may concern:

Be it known that I, Alan Figatner, a citizen of the United States, residing at 1727 53rd Street, Brooklyn, county of Kings, and State of New York, have invented a new, original, and ornamental Design for a Memorial Tablet, of which the following is a specification, reference being had to the accompanying drawing, forming part thereof, and in which—

I claim:

The ornamental design for a memorial tablet, as shown.

ALAN FIGATNER.
